UNITED STATES PATENT OFFICE.

HALVOR H. LYCHE, OF CHICAGO, ILLINOIS, ASSIGNOR TO THE ODIN COMPANY, OF CHICAGO, ILLINOIS, A CORPORATION OF ILLINOIS.

CLOTHES-WRINGER.

1,209,984.

Specification of Letters Patent. Patented Dec. 26, 1916.

Application filed July 6, 1916. Serial No. 107,738.

To all whom it may concern:

Be it known that I, HALVOR H. LYCHE, a citizen of the United States, residing at Chicago, in the county of Cook and State 5 of Illinois, have invented certain new and useful Improvements in Clothes-Wringers, of which the following is a full, clear, and exact specification, such as will enable others skilled in the art to make and use 10 the same, reference being had to the accompanying drawings, forming a part hereof.

My invention relates generally to laundry apparatus, and has reference more particularly to the class of power driven clothes 15 wringers.

One of the main objects of the invention is to improve the construction and increase the efficiency and utility of devices of this character. Another object is the provision 20 in a clothes wringer of a novel carrier device permitting slidable movement of the wringer whereby to assume more than one operative position with reference to its support, and wherein the rolls of the wringer 25 are readily dissociated from the driving mechanism in case of accident occurring to the operator.

These, together with such other objects as may hereinafter appear, or are incident to 30 my invention, I attain by means of the construction illustrated in preferred form in the accompanying drawings, wherein:—

Figure 1 represents a longitudinal vertical sectional view of a wringer embodying 35 my invention, the normal and extended positions of the wringer being respectively indicated by the full and dotted lines; and

Figure 2 is a transverse section of the wringer taken along the line 2—2 of Figure 1.

Referring to the drawings, the numeral 40 3 designates the frame of a power driven wringer and 4 a fragmentary portion of a suitable support therefor, such as for example a laundry tub or washing machine body. Upper and lower rolls 5, 6, are mounted in the standards 7 of the wringer frame 3, and are operatively connected by the gears 8 and 9 in the customary manner, the gears being respectively mounted on the upper and lower roll shafts 10 and 11.

My invention more particularly resides in the provision of a two part carrier device or frame through the instrumentality of which 55 the wringer is capable of being slidably

moved from its normal position illustrated in full lines in Figure 1, whereby to assume a new extended position shown in dotted lines in this figure, in which position the wringing out of articles of clothing from other laundry apparatus, such as a rinsing tub, may take place, at the same time utilizing the power employed for imparting rotation to the rolls 5 and 6 in the normal position of the wringer.

The lower part of this carrier device is provided with a longitudinally extending carrier supporting frame member 12 having a substantially flat central portion 13 and vertical side walls 14 constructed to form 60 the marginal channels 15, said member being mounted on the support 4 and preferably having end walls 16, 17, and the oppositely disposed horizontal extensions 16^a and 17^a (Figure 1).

The numeral 18 indicates a horizontal shaft journaled in bearings 19 and 20 and carrying thereon the loose bevel pinions 21 and clutch 22, such shaft having secured thereon a gear 23 whose upper toothed portion 23^a extends slightly through an opening 24 centrally formed in the portion 13 of the member 12. Meshing with the loose bevel pinions 21, and designed to impart opposite rotation to the shaft 18 through manipulation of the clutch 22 with reference to said pinions, is a bevel gear 25 which is mounted on the end of a vertical drive shaft 26 carried in suitable bearings 26^a. Longitudinal depressions 41, leading from the extension 17^a to stops 27 disposed adjacent the opening 24, are formed in the upper face of the frame member 12 and marginally of its central portion 13 to constitute lower ball race sections for the anti-friction balls 28 normally located in the extension 17^a, the other extension 16^a of the frame member being similarly provided with recesses 29 whereby to seat another set of anti-friction balls 28^a.

The upper part of the carrier device consists of a slidable carrier frame member 30 substantially co-extensive with the support frame member 12, said member carrying the wringer frame 3 and provided with the gear housings 31 and 32 in which the roll shaft 11 has bearings at 31^a and 32^a, the shaft extending to the left through the housing 31 and provided with a handle 11^a.

Secured on the shaft 11, at opposite ends 110

thereof, are driven gears 33 and 34 respectively projecting downwardly through openings 35 and 36 centrally formed in the member 30, the gear 33 being normally in mesh 5 with the driving gear 23 and the gear 34 adapted to be brought into operative driving relation with said gear 23 when the carrier frame 30 is slidably moved to assume its extended position as indicated by the dotted 10 lines in Figure 1. Extensions 31' and 32' are provided to correspond with the extensions 16^a and 17^a and normally rest upon the anti-friction elements to which reference has already been made.

15 As will be seen by an inspection of Figure 2, the carrier frame 30 is marginally formed at its sides with inclined face portions 37 constituting the upper ball race sections for the anti-friction elements and provided also 20 with depending portions 38 bent down into the channels 15, the walls 14 of the member 12 having upwardly and inwardly inclined portions 14^a extending over the inclined face portions 37 of the member 12. In this way 25 the carrier member 30 is maintained against vertical and lateral displacement; and in this connection it is considered preferable to additionally provide guard members 39 depending from each of the housings, 31 and 30 32, to engage the outer faces of the vertical walls 14, and in a manner tending to maintain the verticality of the wringer during the operation of wringing out the clothes. The extension 32' is formed with spacers 40 35 for the balls 28, the inner one of which is adapted to abut the stop 27 when the frame 30 is extended and the outer one normally takes against the end flange 17' of the extension 17^a, (Figure 1). It will be noted 40 that in locating the anti-friction balls and stops 27 at each side of the frame member 12 there can be no interference of these members with the projecting portion of the gear 34 when the member 30 by which 45 it is carried is moved from one position to another.

From the foregoing description, it is deemed apparent that the rolls 5 and 6 receive actuation from the shaft 26 and intermediate gearing mechanism, the direction of movement being governed, as is customary, by the provision of the clutch 22. The operative relation of the gears 23 and 55 33 may be readily dissociated by grasping the handle 11^a and moving the upper carrier frame 30 the required distance. If moved to its extended portions then the gear 34 comes into mesh with the gear 23 and the wringing out process may be then continued 60 from a new feeding point. The handle is also in readiness should it become necessary to adjust the relation of the teeth of upper and lower gears during movement of the wringer to its limiting positions; and furthermore in case the pass of the rolls be-

comes choked, upon movement of the clutch to neutral, the handle may be turned in an opposite direction to release the articles of clothing from the pass in a case where the power when reversed failed to attain the 70 momentum necessary to relieve the situation as here outlined.

What I claim is:—

1. In a machine of the character described, the combination of a wringer provided with 75 rolls and gears for said rolls, a carrier frame secured to the wringer, a support on which the carrier frame is slidably mounted for movement from one operative position to another in a substantially horizontal plane, 80 and gearing operatively carried by said carrier frame and support for actuating the said gears in either position of the carrier frame.

2. In a machine of the character described, 85 the combination of a wringer provided with rolls, a support therefor, a two part carrier frame for said wringer composed of relatively slideable parts, whereby the wringer is adapted to be moved in a substantially horizontal plane from one operative position to another, one part of said frame being associated with the wringer and provided with a pair of gears operatively connected with said rolls, and the other part mounted on 90 the said support and provided with a driving element adapted to engage with either of said gears in the movement of the wringer frame.

3. In a machine of the character described, 100 the combination of a support provided with a power shaft, a wringer provided with rolls, gears for imparting rotation to the rolls, a carrier frame secured to the wringer, and provided with a base, a supporting 105 frame secured to said support in which the base of the carrier frame is slidably mounted for substantially horizontal movement from one operative position to another with reference to said support, and gearing driven 110 from said power shaft for actuating the said gears in either position of the carrier frame.

4. In a device of the character described, the combination of a wringer comprising a 115 frame and its rolls, said wringer adapted to be moved in a substantially horizontal plane from one limiting position to another, a driving element, and driven gearing for said rolls and means by which it may be driven by said element in one position, or when the wringer is moved to the other of its limiting positions, said gearing carried by the frame and disconnectible from the driving element in the horizontal movement of said wringer.

5. In a device of the character described, 125 the combination of a wringer provided with rolls and a base, a support for said base, said wringer adapted for movement relative to said support in a substantially horizontal plane from one operative position to an- 130

- other, a driving element, and driven gearing for said rolls adapted to be actuated by said driving element when the wringer is moved to either of its operative positions, said driven gearing being disconnectible from the driving element in the horizontal movement of said wringer.
6. In a device of the character described, the combination of a wringer comprising a frame and its rolls, gears connecting said rolls and having a shaft extension, a carrier member for said wringer in which said shaft extension is mounted, and provided with a base, a supporting member in which the base of the carrier member is slidably mounted, whereby the wringer is adapted to have movement from its normal operative position to an extended position with reference to said supporting member, driven gearing for said gears extending through said base and operatively carried by said shaft extension, and means by which said gearing may be driven in either position of the wringer.
7. In a device of the character described, the combination of a support having a power shaft, a wringer comprising a frame and its geared rolls, a carrier member for said wringer, a supporting member secured to said support and in which the carrier member is slidably mounted, whereby the wringer is adapted to have movement from one operative position to another with reference to said support, driven gearing for said rolls carried by said carrier member, and means driven by said shaft whereby said gearing may be actuated in both positions of the wringer.
8. In a machine of the character described, the combination of a driving element, a wringer provided with rolls and a base, a support for said driving element and in which said base is slidably received, whereby the wringer is adapted to have movement relative to said support from one operative position to another, anti-friction elements disposed intermediate said base and said support, and driven gearing for said rolls adapted for actuation by said driving element when the wringer is moved to either operative position, said driven gearing movable with the wringer and disconnectible from the driving element in the movement of said wringer.

In testimony whereof I have hereunto signed my name to this specification.

HALVOR H. LYCHE.
